DRAWING MECHANISM

Otto W. Schlums, Whitinsville, Mass., assignor to
 Whitin Machine Works, Whitinsville, Mass., a
 corporation of Massachusetts

Application April 11, 1938, Serial No. 201,342

1. Claim. (Cl. 19—130)

This invention relates to mechanism for drawing textile fibres. While capable of general application, the invention is particularly applicable to the drawing of glass or silicate fibres or other fibres which are of a fragile or brittle nature.

In the ordinary drawing mechanism, as used for instance in drawing cotton fibres, the fibres are gripped between a lower metal driving roll having a fluted surface and an upper or presser roll having a cushioned surface, commonly of leather. But such a combination cannot be used for drawing silicate or similar fibres, as the fluted driving roll breaks the fibres.

A smooth-surface driving roll cannot be used, as slippage between the driving roll and the cushioned roll would produce irregular draft. Furthermore, silicate and similar fibres should be drafted between pairs of rolls which are both cushioned and preferably cork-covered. If a cork-covered roll is driven by the usual fluted roll, however, the cork surface is quickly roughened to such an extent as to make the roll inoperative.

It is the general object of my invention to provide a construction by which a cork-covered or cushioned roll may be effectively driven without destroying the driving surface of the roll.

To the attainment of this object, I provide an upper roll having a cushioned or cork-covered surface of greater length than the yarn transverse, and I provide a lower or driving roll having spaced fluted portions which engage the edge portions only of the cushioned or cork surface of the upper roll, which edge portions are beyond the range of yarn traverse. That portion of the lower roll which engages the middle portion or working surface of the upper roll is provided with a smooth and polished surface which can have no roughing effect on the cork-covered upper roll.

Such a driving combination may have a single cushioned upper roll for each lower driving roll, as used in drafting rayon, celanese, fine cotton and other fine fibres, or may have a pair of upper rolls for use in drafting silicate or other similar fibres.

My invention further relates to arrangements and combinations of parts which will be herein-after described and more particularly pointed out in the appended claim.

Preferred forms of the invention are shown in the drawing, in which

Fig. 1 is a sectional end elevation of a portion of a drawing mechanism embodying my improvements;

Fig. 2 is substantially a front elevation of the

parts shown in Fig. 1, looking in the direction of the arrow 2 and with certain parts shown in section; and

Fig. 3 is an end elevation showing my invention as applied to the drafting or rayon or other fine but not brittle fibres.

Referring to Figs. 1 and 2, I have shown mechanism particularly designed for drawing or drafting silicate fibres and comprising lower or driving rolls 10 supported in bearing brackets 11 mounted on a frame 12. Any desired number of driving rolls 10 may be provided and two such rolls are shown in the drawing.

Upper and lower top rolls 20 and 21 are provided for each driving roll 10, and these top rolls 15 are each preferably provided with a cork or cushioned surface. In the preferred construction, a pair of upper top rolls 20 are mounted on a short shaft 22, and a pair of lower top rolls 21 are mounted on a short shaft 23. The ends of 20 the shafts 22 and 23 are received in substantially vertical guideways 24 formed in the sides of fixed stands 25.

The top rolls are thus mounted for free movement vertically but may be pressed downward 25 against the driving rolls 10 by weights or springs, acting through links 30 and top roll saddles 31 which may be of any usual construction.

Referring to Fig. 2, it will be seen that the lower top rolls 21 are substantially wider than the upper 30 top rolls 20, and that the driving roll 10 has smooth-surfaced portions 33, each substantially equal in width to a top roll 20 and bordered by knurled or fluted portions 34 which engage the edge portions of the superposed lower top roll 21. 35

The portions 33 and 34 of the driving roll 10 are of substantially equal diameter, the knurled or fluted portions 34 being only a few thousandths larger than the smooth portions 33. Consequently each lower top roll 21 engages portions 40 33 and 34 of a driving roll throughout its full width, the engagement of the roll 21 with the portions 34 being sufficient to prevent relative slippage between the rolls.

Traverse rods 40 and traverse guides 41 are provided for the different sets of rolls, and the traverse of the yarns Y is limited thereby, so as not to exceed the width of the upper top rolls 20 or the width of the smooth portions 33 of the driving rolls.

With this construction, the center portions of the lower top rolls 21 which are engaged by the upper rolls 20 and by the yarns Y do not come into contact with the fluted or knurled portions 34 of the driving rolls 10, but only with the mid- 55

idle portions 33 of the rolls 10 which have smooth polished surfaces. The rolls 21 are thus driven at predetermined speed and maintain uniform draft, while at the same time the yarn-engaging portions of their surfaces do not become roughened or inoperative by engagement with a fluted or knurled driving surface of the roll 10.

I am thus able to perform drawing operations between pairs of cork-covered or cushioned rolls, 10 while at the same time maintaining uniform draft. The mounting of the rolls 20 and 21 on short shafts, as 22 and 23, facilitates removal of the rolls for occasional buffing.

In Fig. 3, I have shown my invention embodied 15 in drawing mechanism suitable for use with cotton, rayon or other similar fibres in which the drawing takes place between driven lower rolls 50 and cushioned upper rolls 51. It will be understood that the lower rolls 50 are formed like the 20 rolls 10 shown in Fig. 2, and that they contact with the top rolls 51 outside only of the range of traverse of the yarn Y'.

My invention as thus applied to the drafting of cotton or rayon or similar fibres possesses an 25 important advantage over the usual drafting by fluted rolls in that the smooth polished surfaces of the rolls 50 which engage the yarn do not load up with lint, dirt and short fibres, as frequently happens with fluted rolls. This avoids the frequent cleaning of the rolls previously necessary 30 from time to time to prevent accumulations of

dirt and lint from being carried into the yarn, with detrimental effects.

This method of roll driving may be utilized in any machine in which fibres are drafted between pairs of rolls.

Having thus described my invention and the advantages thereof, I do not wish to be limited to the details herein disclosed, otherwise than as set forth in the claim, but what I claim is:

In a drawing mechanism having a driving roll 10 with spaced operative sections and having upper and lower cushioned top rolls between which the silver passes, the feature that the lower top rolls are wider than the upper top rolls, that the operative sections of the driving roll are substantially 15 equal in width to the width of the lower top rolls, and that each section of the driving roll comprises a smooth middle portion corresponding in width to the width of the upper top roll and a roughened driving portion at each side of said 20 smooth portion, said smooth and roughened portions being of substantially equal diameters and simultaneously engaging the cushioned surface of said lower top roll, that part of said lower top roll which has drawing engagement with said upper top roll being itself engaged only by the 25 smooth middle portion of the associated driving roll section, whereby roughening of the coating drawing surfaces is avoided.
